UNITED STATES PATENT OFFICE.

ALFRED BRUNO SEPPMANN, OF LAKE CRYSTAL, MINNESOTA.

COTTER-KEY PULLER.

1,403,919.

Specification of Letters Patent. Patented Jan. 17, 1922.

Application filed May 5, 1921. Serial No. 467,162.

To all whom it may concern:

Be it known that I, ALFRED BRUNO SEPPMANN, a citizen of the United States, residing at Lake Crystal, in the county of Blue Earth, State of Minnesota, have invented a new and useful Cotter-Key Puller; and I do hereby declare the following to be a full, clear, and exact description of the invention, such as will enable others skilled in the art 10 to which it appertains to make and use the same.

The invention relates to cotter key removers and has for its object to provide a tool by means of which a cotter key may be 15 removed from positions on machinery where the same cannot be reached by means of conventional tools, such for instance as pliers. Also to provide a tool by means of which a cotter key can be removed even when the 20 eye of the cotter key extends in a direction away from the operator, thereby providing a tool applicable to the varying conditions under which cotter keys have to be removed.

A further object is to provide a cotter key 25 puller comprised of a shank and a handle member, said shank having slideably mounted thereon between abutments a hammering element by means of which hammering element and abutments a downward or upward 30 movement of the shank may be obtained for pushing or pulling a cotter key from its position.

A further object is to provide the lower 35 end of the shank with an outwardly and upwardly curved horn for engaging in the eye of the cotter key during a cotter key pulling operation. Also to provide the lower end of the shank with an outwardly and downwardly extending horn adapted to be disposed in the eye of the cotter key when 40 said eye is disposed away from the operator and a downward movement of the tool as a whole is necessary to remove the key.

With the above and other objects in view, 45 the invention resides in the combination and arrangement of parts as hereinafter set forth, showing the drawings, described and claimed, it being understood that changes in the precise embodiment of the invention may 50 be made within the scope of what is claimed without departing from the spirit of the invention.

In the drawings:

Figure 1 is a side elevation of the cotter 55 key remover.

Figure 2 is an enlarged sectional view through the slideable hammer.

Figure 3 is a horizontal sectional view taken on the line 3—3 of Figure 1.

Referring to the drawings, the numeral 1 60 designates the handle of the tool, and 2 the shank carried thereby; the shank 2 may be of any length desired so that it will easily reach various parts of an engine. The lower end of the shank 2 is provided with an 65 outwardly and upwardly curved integral horn 3 which engages the eye 4 of a cotter key 5 when said key is being pulled. Horn 3 is particularly adapted for removing cotter keys when the eye of the key extends in 70 the direction of the operator. However, at times the eye does not extend in the direction of the operator but on the contrary extends away from the operator. When the eye extends away from the operator, the horn 75 6 which extends outwardly and downwardly is placed in engagement with the eye 4 of the cotter key in such a manner that upon a movement of the shank 2 in the direction of the arrow *a* the cotter key will be forced 80 from its position. However, when the cotter key is in the position shown in Figure 1, the action is substantially a pulling one and the shank 2 is moved in the direction of the arrow *b*. 85

It has been found that cotter keys become stuck incident to corrosion and from other causes, therefore, they cannot be removed by simply a pulling or pushing action on the tool and require a hammering action to 90 break the corrosion and where the end of the key has been spread to bend the arms of the end to normal position. To accomplish this result, the shank 2 is provided with spaced abutments 7 and 8 and between 95 which abutments a slideable hammer 9 is mounted on shaft 2. During a cotter key removing operation, the operator grasps the handle 1 with one hand and with the other hand reciprocates the hammer 9 on the shank 100 2. During the reciprocation of the hammer 9 a hammering action is imparted on the abutment 7 or 8 according to the direction it is desired to move the shank. This hammering action starts the key from the aperture 105 in which it is disposed and quickly removes the key without bending or destroying the same.

From the above, it will be seen that a cotter key remover is provided which is 110

simple in construction and one wherein the parts are reduced to a minimum.

The invention having been set forth what is claimed as new and useful is:

5 A cotter key remover comprising a handle member and a shank, key engaging arms carried by the lower end of said shank, one of said arms extending outwardly and curving upwardly, the other arm extending outwardly and downwardly, spaced abutments

carried by the shank, and a slideable hammer member slideably mounted on the shank and disposed between said abutments.

In testimony whereof I have signed my name to this specification in the presence of 15 two subscribing witnesses.

ALFRED BRUNO SEPPMANN.
